UNITED STATES PATENT OFFICE

2,684,434

SURVEYOR'S ILLUMINATED TARGET

Andrew K. Burey, Youngstown, Ohio

Application May 3, 1951, Serial No. 224,417

1 Claim. (Cl. 240--6.4)

2

This invention relates to targets and more particularly to illuminated targets for use in connection with rods or staffs as used by surveyors in determining various levels and the like.

The principal object of the invention is the provision of an illuminated target.

A further object of the invention is the provision of an attachment for a conventional target whereby the same may be illuminated.

A still further object of the invention is the provision of an illuminated target incorporating means for securing the target on the surveyor's rod.

A still further object of the invention is the provision of an illuminated target incorporating signaling means.

A still further object of the invention is the provision of an attachment incorporating a light source and a signaling device and registerable with the upper half of a conventional circular target so that the same may be mounted thereon and used in conjunction therewith without effecting the appearance thereof.

The surveyor's target disclosed herein may comprise either one of two forms, the first of which comprises an illuminating device attachable to the upper half of a conventional target and the other of which comprises a replacement target incorporating the illuminating device as a part thereof. The preferred embodiment of the invention lies in the attachment for a conventional target and wherein an illuminating means and a signaling means is provided and which attachment may be readily attached to a conventional target or removed therefrom as desired.

The illuminated target disclosed herein enables a survey, including various levels, to be made despite unsatisfactory lighting conditions which otherwise render indistinct the calibrated indicia on the rod and which are determined by the surveying party in striking a satisfactory level.

It is well known in the surveyor's art that a surveying party usually comprises a transit and a rod and target combination. The transit is generally located a substantial distance from the rod and target and requires the vertical adjustment of the target on the rod to cause it to be properly aligned with respect to the transit. It has heretofore been necessary for the operator of the transit to rely on the general lighting when viewing the target through the transit and the present invention enables the target to be viewed more distinctly by providing an illuminating means whereby the target and the indicia indicated thereby may be viewed despite poor general

lighting conditions. The illuminated target disclosed herein is light in weight, inexpensive in construction and is of no greater size than the conventional targets heretofore used by surveyors.

With the foregoing and other objects in view which will appear as the description proceeds, the invention resides in the combination and arrangement of parts and in the details of construction hereinafter described and claimed, it being the intention to cover all changes and modifications of the example of the invention herein chosen for purposes of the disclosure, which do not constitute departures from the spirit and scope of the invention.

The invention is illustrated in the accompanying drawing, wherein:

Figure 1 is a front plan view of a surveyor's illuminated target.

Figure 2 is a back view with parts broken away.

Figure 3 is a front plan view of the target illuminating attachment.

Figure 4 is a back plan view thereof.

Figure 5 is a vertical section on line 5—5 of Figure 1.

Figure 6 is a vertical section on line 6—6 of Figure 3.

By referring to the drawings and Figure 1 in particular it will be seen that a surveyor's target of customary size and shape is disclosed and comprises a circular body member 10 having a vertically standing, rectangular opening 11 centrally thereof. The body member 10 is divided into

three sections by substantially vertical lines 12, the central portion being preferably white in color and the two side portions preferably being red in color. The body member 10 may also be divided by vertical and horizontal center lines

and the four quarters of the device thus defined painted alternately red and white as is customary in the art. The target shown in Figure 1 of the drawings is provided with a clamp for engagement with the side of a rod (not shown), the clamp being actuated by a knurled knob 13.

The target is adapted to be slidably positioned on a vertical rod (not shown) by the engagement therewith of a pair of oppositely disposed in-turned flanges 14 as best illustrated in Figure 2 of the drawings, the same being formed vertically on the back of the body member 10 and one on either side of the opening 11. The opening 11 has a transparent indicia strip 15 positioned partly thereover so as to overlie the scale or other indicia formed on the rod on which

the target is normally positioned. The uppermost portion of the body member 10 is provided with a removable housing 16 open at its lower portion and concealing an incandescent bulb 17 which is so positioned as to adequately illuminate the portion of the rod visible through the opening 11 heretofore referred to. As may be seen by referring to Figures 2 and 3 of the drawings, the incandescent bulb 17 is positioned well in front of the opening 11 and in Figure 3 of the drawings dotted lines indicate the positioning of the rod 18, the front or indicia portion thereof being indicated by the numeral 19. It will be observed that light rays from the incandescent bulb 17 pass through the opening 11 and illuminate the entire surface of the rod 18.

The back portion of the target 10 is provided with a pair of battery retaining boxes 20 and a switch 21 which is in circuit with an electrical conductor 22 which establishes electrical connection between the batteries 23 and the incandescent bulb 17. It will thus be seen that the target 10 is of a conventional size and shape, that it is therefore capable of being used as a replacement for a conventional target and that it may be positioned on the rod 18 and secured in desired position by manipulation of the knob 13 which moves a clamping piece 24 into frictional engagement with the side of the rod 18.

Figures 3, 4 and 6 of the drawings show an adaptation of the illuminated target hereinbefore referred to in that an illuminated attachment including a body member 25 is disclosed as being movably positioned on the upper half of a conventional circular target 26. The body member 25 has an arcuate upper portion and a horizontal base 27 and is of a size to enable the horizontal base 21 to overlie a horizontal center line on a conventional target 26. A notch 28 is formed in the lower central portion of the body member 25 and corresponds with the upper half of a rectangular opening 29 in the conventional target 26.

In Figure 3 of the drawings a front plan view of the target illuminating attachment is disclosed and by referring thereto it will be seen that the body member 25 includes a colored circular lens 30 at the uppermost central portion thereof and a pair of switches 31 and 32. The switch 31 controls an incandescent bulb 33 located adjacent 50 the lens 30 and the switch 32 controls an incandescent bulb 34 located immediately above the upper portion of the notch 28.

In Figure 4 of the drawings a back panel of the target illuminating attachment is shown re- 55

moved and batteries 35 are shown positioned in sockets 36 and electrically connected by means of conductors 37 and 38 with the switches 31 and 32 heretofore referred to so that the incandescent bulbs 33 and 34 may be controlled thereby.

By referring to Figures 4 and 6 of the drawings it will be seen that the body member 25 has a pair of oppositely disposed rearwardly extending arcuate clamping sections 39, a set screw 40 being positioned through each and registerable with the back of a conventional target 26. The target illuminating attachment is thereby capable of being secured to a conventional target 26. It will occur to those skilled in the art that the incandescent bulb 34 may alternately be located at either side of the notch 28 in which position it will adequately illuminate the face of the rod on which the target is positioned and which in turn carries the attachment comprising the body member 25.

It will thus be seen that either form of the invention enables the several objects of the invention disclosed herein to be achieved.

Having thus described my invention, what I claim is:

In a surveyor's target including a body member having an opening therein and means for slidably positioning said body member on a surveyor's rod so that indicia thereon is visible through said opening, an incandescent bulb positioned in the upper front portion of the body member and at one side of said opening therein, said body member forming a hood normally covering said incandescent bulb and having a secondary opening enabling the light from the incandescent bulb to enter said first mentioned opening, a battery box formed on the back of said target, a battery in said box and a circuit including a switch connecting said bulb and said battery.
